UNITED STATES PATENT OFFICE.

NELSON ROY KINDER, OF WEST FRANKFORT, ILLINOIS.

STOKER-OPERATING MEANS.

Application filed May 10, 1923. Serial No. 638,057.

To all whom it may concern:

Be it known that I, NELSON ROY KINDER, a citizen of the United States, residing at West Frankfort, in the county of Franklin 5 and State of Illinois, have invented certain new and useful Improvements in Stoker-Operating Means; and I do declare the following to be a full, clear, and exact description of the invention, such as will enable others 10 skilled in the art to which it appertains to make and use the same.

My invention relates to stoker operating mechanisms of the type in which a driven proceeding and receding rod or other member, is used for alternately moving an arm or other stoker actuator in opposite directions, the object being to provide a simple, inexpensive and efficient association of parts for permitting more or less lost motion between the driven proceeding and receding member and the stoker actuator, so as to operate the stoker more or less vigorously, according to requirements.

With the foregoing in view, the invention 25 resides in the novel subject matter herein-after described and claimed, the description being supplemented by the accompanying drawing.

Figure 1 is a side elevation showing a 30 stoker operating mechanism constructed in accordance with my invention.

Figure 2 is a horizontal sectional view on line 2—2 of Fig. 1.

Figure 3 is an enlarged vertical sectional 35 view as indicated by line 3—3 of Fig. 2.

In the drawing above briefly described, the numeral 1 designates an arm extending from a shaft 2 and constituting an actuator for a stoker, said arm being formed with a 40 guide 3. A rod 4 passes loosely through the guide 3 and means are provided for constantly imparting a proceeding and receding motion to said rod, a pitman 5 and driven eccentric 6 being shown for this purpose.

The eccentric is mounted on a shaft 7 which 45 may be rotated by any desired means.

In the present showing, the rod 4 is provided with a shoulder in the form of a collar 8, to strike the guide 3 and move the actuator 1 in one direction, while a body 9 is adjustably mounted on said rod to strike the actuator and move it in the opposite direction. It will be seen that if the collar 8 and the body 9 are in close relation with the actuator, the latter will be rather vigorously

operated by the rod 4. However, if lost motion is permitted between the rod and actuator, the stoker will be operated more slowly. I provide means whereby adjustments of the body 9 along the rod, may be automatically effected, this adjusting means being adapted to be operated by a balanced-draft control associated with the furnace on which the stoker is used, or other automatic control means may be used. It thus follows that if the fire needs a comparatively large amount of fuel, the body 9 is automatically moved into close relation with the actuator 1 and thus the reciprocation of the rod will operate the stoker to maximum capacity, but as less fuel is gradually needed, the body 9 is automatically adjusted away from the actuator 1 and consequently the stoker will be operated in a manner to supply only the required amount.

In the preferred form of construction, the bore 10 of the body 9 is threaded only throughout a portion of its length, as disclosed at 11 in Fig. 3 and the unthreaded portion of said body extends beyond the 80 threads 12 on the rod 4, with which the threads 11 are engaged. Thus, it will be seen that the threads 12 are prevented from dragging upon the guide 3 and consequently there is no possibility of injuring them. An 85 operating chain or other flexible element 13 is wound around the cylindrical outer surface of the body 9, in the preferred form of construction, one end of said chain being passed over a sheave 14 and having a weight 90 15, while the other end of said chain is connected with a reducing sheave 16, from which a chain or the like 17 leads to a balanced draft control or other automatic control means. It will thus be seen that as 95 the chain 17 is moved in one direction or the other, the chain 13 will be similarly moved and will consequently rotate the body 9 to effect adjustment thereof on the rod 4.

To insure smooth operation of the chain 13, I prefer to provide the periphery of the body 9 with a helical guide groove 18 in which the chain is received, and any desired means such as the cap screw 19, shown in Fig. 3, may be employed to prevent slipping of the chain upon the body.

By employing the construction disclosed or a substantial equivalent thereof, it will be obvious that a simple and inexpensive, yet a sensitive and efficient mechanism has 110

been provided for automatically controlling a stoker of any desired form.

Excellent results are obtainable from the details disclosed and they are therefore preferably followed, but within the scope of the invention as claimed, numerous changes may be made.

I claim:

1. Stoker control means comprising a stoker actuator adapted to be moved alternately in opposite directions, a driven proceeding and receding member movable with respect to said actuator, a body turnably mounted on said driven member and movable bodily therewith to transmit movement in one direction to said actuator, means adapted to be actuated by an automatic control for turning said body on said driven member, means for utilizing the turning movement of said body to effect adjustment thereof with respect to said stoker actuator, and means for returning said stoker actuator after each movement thereof by said body.

2. Stoker control means comprising a stoker actuator adapted to be moved alternately in opposite directions, a driven proceeding and receding member movable with respect to said actuator, a body threaded on said driven member and adapted to move said stoker actuator in one direction, means adapted to be actuated by an automatic control for turning said body to adjust the same along said driven member and vary its relation with said stoker actuator, and means for returning said stoker actuator after each movement thereof by said body.

3. A structure as specified in claim 1; said control actuated means including a flexible element wound upon said body.

4. A structure as specified in claim 1; said control actuated means including a flexible element wound upon said body, a sheave over which the free end of said element is wound, and a weight on said free end.

5. Stoker control means comprising a

stoker actuator having a guide and adapted to be moved alternately in opposite directions, a driven proceeding and receding rod passing slidably through said guide and having a shoulder to strike said guide and move the actuator in one direction, a body adjustable along said rod and adapted to strike said guide and move the actuator in the other direction, and adjusting means for said body adapted for connection with automatic control means to be operated thereby.

6. Stoker control means comprising a stoker actuator having a guide and adapted to be moved alternately in opposite directions, a driven proceeding and receding rod passing slidably through said guide and having a shoulder to strike said guide and move the actuator in one direction, a body threaded adjustably on said rod and adapted to strike said guide to move the actuator in the other direction, and means adapted for connection to an automatic control for rotating said body to adjust it along said rod.

7. Stoker control means comprising a stoker actuator having a guide and adapted to be moved alternately in opposite directions, a driven proceeding and receding rod passing slidably through said guide and having a threaded portion, a rotatable body having a bore receiving said rod, said bore being threaded throughout only a portion of its length with its threads engaging the threads of said rod, the unthreaded portion of said body extending toward said guide beyond the threaded portion of the rod to strike said guide and move the actuator in one direction and to prevent the threads of the rod from contacting with said guide, means for returning said actuator and guide after each movement thereof by said body, and means connected with said body and adapted to be operated by an automatic control for rotating and adjusting said body.

In testimony whereof I have hereunto affixed my signature.

NELSON ROY KINDER.
